(57) **CLAIM**

The ornamental design for an inhaler, as shown and described.

DESCRIPTION

FIG. 1 is a front perspective view of an inhaler of our design.

FIG. 2 is a rear perspective view of the inhaler of FIG. 1.

FIG. 3 is a right side view of the inhaler of FIG. 1.

FIG. 4 is a left side view of the inhaler of FIG. 1.

FIG. 5 is a front view of the inhaler of FIG. 1.

FIG. 6 is a rear view of the inhaler of FIG. 1.

FIG. 7 is a top view of the inhaler of FIG. 1; and,

FIG. 8 is a bottom view of the inhaler of FIG. 1.

Broken lines shown in the figures are included for the purpose of illustrating portions of the inhaler and form no part of the claimed design.
